Des. 212,190
Patented Sept. 10, 1968

212,190

CHRISTMAS TREE ORNAMENT

Jerome L. Asner, 2604 SW. 65th St. 73159, and Edward N. Campbell, 4068 NW. 61st St. 73112, both of Oklahoma City, Okla.

Filed July 5, 1967, Ser. No. 7,712

Term of patent 14 years

(Cl. D29—1)

FIGURE 1 is a view in elevation of a Christmas tree ornament illustrating our new design.

FIGURE 2 is a plan view of the Christmas tree ornament illustrating our new design as it appears when viewed from above.

FIGURE 3 is a sectional view taken along line 3—3 of FIGURE 2.

FIGURE 4 is a bottom view of the Christmas tree ornament incorporating our new design as it appears when viewed from below.

FIGURE 5 is a sectional view taken along line 5—5 of FIGURE 2.

We claim:

The ornamental design for a Christmas tree ornament, substantially as shown.
